UNITED STATES PATENT OFFICE.

WILLIAM SCHOLL, OF MARION, PENNSYLVANIA.

PULLEY-BLOCK.

SPECIFICATION forming part of Letters Patent No. 268,044, dated November 28, 1882.

Application filed August 4, 1882. (No model.)

To all whom it may concern:

Be it known that I, WILLIAM SCHOLL, of Marion township, in the county of Berks and State of Pennsylvania, have invented certain new and useful Improvements in Pulley-Blocks; and I do hereby declare that the following is a full, clear, and exact description thereof, reference being had to the accompanying drawings, and to the letters of reference marked 10 thereon, which form part of this specification, and in which—

Figure 1 is a side elevation of my improved pulley-block, showing a sectional tenoned ring applied to the block. Fig. 2 is an edge view 15 of the parts represented by Fig. 1. Fig. 3 shows an open swivel-ring adapted for the pulley-block of Figs. 1 and 2 when the sectional tenoned ring is removed. Fig. 4 is a perspective view a swivel-yoke which is interchangeable with the said tenoned ring and swivel-ring.

This invention relates to improvements applicable to pulley-blocks; and the nature of my invention consists in a pulley-block formed 25 entire, and provided with a sheave and a removable attaching device; also, in a pulley-block having flaring openings for the passage of the rope, a mortise adapted to receive a tenon formed on a ring or yoke, eyes to receive 30 ropes or hooks, and a provision for a sheave or pulley; also, in a tenoned ring or yoke which is adapted for use in suspending the pulley-block from a hook, ring, or other object, as will be fully understood from the following description, when taken in connection with the annexed drawings.

The letter A designates the pulley-block, and B the grooved rope pulley or sheave, which latter is applied between the two jaws or cheeks 40 of the block, and is allowed to turn freely about a bolt, C, which passes transversely through the said cheeks and receives a nut, a, on one end.

The ends of the cheeks or jaws of the pulley-blocks are concave vertically, as indicated by f, and when taken horizontally these ends flare outwardly and upwardly, as indicated by b, Fig. 2. By thus shaping the open ends of the block A the rope is freely guided on the

pulley, both in entering and leaving the block, 50 and it will be impossible for the rope to kink or to be cut or unduly abraded, for the reason that rounded guiding-surfaces are presented to it on its way from and to the pulley-block.

The head of the block A is constructed with 55 eyes E E, which are adapted to receive ropes, hooks, or rings, and between these eyes E E is a mortise cast into the block and designed to receive tenons, as will be hereinafter explained. The head of the block A is also constructed with flat and cylindrical bosses, which are in the center of the block, and which are perforated laterally to receive the bolt C, that receives the nut a on one end of it, as above described.

Fig. 1 indicates a pulley-block of the construction above described, and which is provided with a divisible ring, H. This ring is composed of two sections, b b', divided horizontally and vertically. The horizontal division is directly through the ring, and the vertical portion is through the half-tenons c c', which are perforated, as shown, and adapted to receive through the scored portions the bolt C'. This bolt securely holds the said divided ring in place, and by removing it (the bolt) the ring can be coupled to another ring, link, or any other object adapted to receive it.

Instead of using the ring H, I may substitute a hook, H', having a swivel-tenon, c'', applied to it. This hook is provided with lips, through which a screw, i, is applied for readily closing the opening, and it is also provided with a double-beveled stop, d, for checking the lateral vibration of the block A. The tenon c'' is 80 intended to enter the mortise in the block A, and to be secured thereto by the bolt C.

The Fig. 4 is a yoke having perforations f' f' vertically through it and eyes n n transversely through its ends. This yoke, which I 90 now letter J, is adapted to receive ropes for attaching it to a beam or other object, and it is constructed with a swivel-tonon, c'', precisely like the tenon c'' on the hook H'.

It will be seen from the above description 95 that I have a pulley-block formed entire, with eyes to which a tackle can be attached, and with flaring-edge jaws which will prevent

kinking of the rope, and also with a tenon receiver or mortise to receive a link, a hook, or a yoke, as I have above described.

Having described my invention, I claim—

5 The combination, with the pulley-block, having a socketed head, of a split ring having a split tenon and a coupling-bolt passing transversely through the said pulley-block head and through the tenon, constructed and operating

substantially in the manner and for the purposes described.

In testimony that I claim the foregoing as my own I affix my signature in presence of two witnesses.

WILLIAM SCHOLL.

Witnesses:

GEORGE P. SCHULTZ,
JACOB LAUCKS.
